CHARLES C. BUCKLEY AND LOUIS DOVELL, OF NEWARK, NEW JERSEY.

Design No. 2,533, dated January 1, 1867.

DESIGN FOR A TRADE MARK.

The Schedule referred to in these Letters Patent and making part of the same.

TO ALL WHOM IT MAY CONCERN:

Be it known that we, CHARLES C. BUCKLEY and LOUIS DOVELL, have produced or designed a new Trade Mark; of which the following is a full, clear, and exact description, reference being had to the accompanying specimen and drawing that make part of this specification.

An oval or elliptical border, formed with an outer heavy line and an inner light line, encloses a space in which are engraved the initials of the firm in flourished capital writing letters, the common sign for the article, and being connected in the flourish at the back of the letter D, as shown at 'A. The other portions of the label matifuge, we claim the design for a trade mark, substantially as shown and described.

CHAS. C. BUCKLEY,
LOUIS DOVELL.
